(57) **CLAIM**

The ornamental design for a ring, as shown and described.

DESCRIPTION

FIG. 1 is a top, front and right side view of a ring showing my new design;

FIG. 2 is a top plan view thereof;

FIG. 3 is left side elevational view thereof, the right side elevational view being identical thereto;

FIG. 4 is a front elevational view thereof, the back elevational view being identical thereto;

FIG. 5 is a bottom plan view thereof; and,

FIG. 6 is a bottom, front and right side perspective view thereof.

The broken lines shown in the figures represent portions of the ring which form no part of the claimed design.
